INVENTOR
Bryan P. Joyce
BY
W. H. Roach
ATTORNEY

UNITED STATES PATENT OFFICE.

BRYAN P. JOYCE, OF DAVENPORT, IOWA.

SEPARABLE GUN CARRIAGE.

Application filed October 1, 1923. Serial No. 665,866.

(FILED UNDER THE ACT OF MARCH 3, 1883, 22 STAT. L., 625.)

To all whom it may concern:

Be it known that I, BRYAN P. JOYCE, a citizen of the United States, and a resident of Davenport, county of Scott and State of Iowa, have invented an Improvement in Separable Gun Carriages, of which the following is a specification.

The invention described herein may be used by the Government, or any of its officers or employees in prosecution of work for the Government, or by any other person in the United States, without payment to me of any royalty thereon, in accordance with the act of March 3, 1883.

The present invention relates to separable gun carriages and particularly to that type of carriage adapted to accompany infantry troops on the advance.

The primary object of my invention is the provision of a gun carriage which may be knocked down for convenience in transportation.

Another object of this invention is the provision of a gun carriage in which the traversing mechanism is embodied in the means for connecting the gun carriage proper to the support therefor.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings wherein:

Fig. 1 is a plan view of the gun carriage;

Fig. 2 is a view in side elevation;

Fig. 3 is a partial sectional view showing the elevating and traversing mechanism; and

Fig. 4 is a detail sectional view of the elevating mechanism.

Referring to the drawing by numerals of reference:

I have shown at 5 a gun carriage support.

ed in its firing position by a spade 6 and carriage wheels 7 connected together by an axle 8. The spade is provided with aligned apertures 9 adapted to receive a pin to lock the spade upon the limber in travel.

In the preferred embodiment of my invention the gun carriage is provided with trail members 10 and 11 which are attached at one end to the spade 6. These trail members are made of angle iron and are trunnioned by means of brackets 12 on sleeves 13 of a housing 14. The housing 14 is adapted to receive the carriage axle which is screw threaded as at 15 for a portion of its length. One of the sleeves of the axle housing is threaded as at 16 to engage with the threads on the axle so as to traverse the axle housing and the trail members connected thereto on the axle on rotation of the axle.

The wheels 7 are journaled on the axle in the usual manner and are retained thereon by offsets 17 on the axle against which the inner sides of the wheel hubs seat and by nuts 18 threaded on the axle and seating against the outer sides of these hubs. At one end the axle is provided with an extension 19 and squared on this extension is a hand wheel 20 for manipulating the axle to traverse the trails.

In the preferred embodiment of my invention the housing 14 intermediate the trail members 10 and 11 is formed with a chamber 21 separated by a partition 22 from the axle housing proper. This chamber 21 is adapted to contain the elevating mechanism for the gun which in the preferred embodiment of my invention comprises a series of telescoping members 23, the outer members 23^a and 23^b of which are hollow and internally and externally screw-threaded to engage with one another and the inner member 23^c of which is externally screw threaded and adapted to intermesh with the internal threads of the next succeeding member 23^b. While I have chosen to employ three such telescoping members, 23, it is obvious that their number may be decreased or increased at will to suit the particular type of gun used.

The outer telescoping member 23^a is secured to the trunnion 42 and connected by links 55 and 56 to the sight bracket. The outermost of the telescoping members 23 is provided with an aperture 31 adapted to receive a key 32 attached by means of a chain 33 to the gun cradle 36. This key passes through the aperture 31 and registering apertures 34 formed in lugs 35 on the gun cradle 36.

10 The gun barrel 37 may be mounted on the cradle in any suitable manner. As shown a casing 38 is provided which is adapted to enclose the gun barrel. On either side of the cradle are attached angle 15 iron members 40 which extend rearwardly of the cradle and are fastened by means of Y-clips 41 to a trunnion 42 mounted in brackets 43 on the trail members 10 and 11. The Y-clips are detachably secured to the 20 trunnion by means of pins 44 passed through registering apertures in the clips and trunnion and secured by means of chains 45 to the rearwardly extending arms 40. With a cradle mounting such as described the cradle in elevation is adapted 25 to move in an arc whose center is the trunnion 42.

The gun barrel may be fastened to the cradle against removal in travel or preferably may be releasably fastened thereto in a manner such as described in my co-pending application Serial No. 665,867, filed October 1, 1923.

Any suitable recoil mechanism may be 45 employed for counteracting the recoil of the gun when fired. As shown a cylinder 46 is secured to the casing 38. A piston 47 is reciprocally mounted in this cylinder and secured to the gun barrel by means of the 50 locking member 48 hinged at one end between lugs 50 formed on the gun barrel and secured in locking position between said lugs by means of a spring pressed plunger 51 mounted in a lug on the gun barrel. In 55 this manner the piston is secured to the gun barrel so as to move therewith in recoil and in counter recoil.

The usual sighting mechanism 52 is provided and the sighting mechanism is carried 60 on the trail member 11 which trail member extends somewhat beyond the axle 8 and is secured to said trail member by a bracket 53 pivoted to the trail member.

Movement of the gun is transmitted to 65 the sight by means of a bracket 54 fixedly

secured to the trunnion 42 and connected by links 55 and 56 to the sight bracket.

The gun may be adjusted by manipulation of the hand wheel 20 and 29 for firing and may be knocked down for transport for 70 carriage by mules or the troops serving the gun. In order to separate the parts of the gun carriage for convenience in transport the left wheel of the carriage is first removed from the axle and the axle then unthreaded 75 from the axle housing; the cradle is then detached from the elevating mechanism by removal of the key 32 and from the trail by removal of the pins 44; the gun itself may then be disengaged from the cradle by 80 releasing the locking member 48. When knocked down the gun barrel itself serves as one load, the cradle and casing as another load, the trail members and spade as a third load and the axle, wheels and sight is a 85 fourth load.

I claim:

1. A separable gun carriage, including a trail, a gun cradle supported on the trail, wheels for said carriage, an axle connecting 90 said wheels, an axle housing fast on said trail and adapted to receive said axle, cooperating means on the axle and axle housing for traversing said trail, means in said axle housing for elevating said gun, means 95 for detachably connecting said cradle to said elevating means, a trunnion on the trail and means for detachably connecting said cradle to said trunnion.

2. A separable gun carriage, including a 100 trail, a gun cradle supported on said trail, means for supporting said trail, a member connecting said trail to said support, a housing on said trail to receive said connecting member, cooperating means on said 10 housing and connecting member for traversing said trail, means in said housing for elevating the gun, means for detachably connecting the gun cradle to the elevating means, means for hingedly connecting the 11 cradle to the trail and means for detachably connecting the cradle to said hinge means.

3. A separable gun carriage, including a trail, wheels for supporting the carriage, an axle connecting said wheels, an axle 11 housing fast on said trail and adapted to receive said axle, cooperating means on the axle and axle housing for traversing the trail, a gun cradle, means for detachably connecting the gun cradle to the axle housing and means detachably connecting the gun cradle to the trail.

4. A separable gun carriage including a trail, a gun cradle supported on said trail, wheels for said carriage, an axle connecting said wheels, an axle housing fast on said trail and adapted to receive said axle, cooperating means on the axle housing and axle for traversing the trail and means in said axle housing for elevating the gun.

5. A separable gun carriage including a trail, means for supporting the trail, means connecting said trail to its support, a housing on said trail adapted to receive said connecting means, an elevating mechanism in said housing, a cradle, means connecting said cradle to the elevating mechanism, a trunnion on said trail, means rigidly connecting said cradle to said trunnion, a bar attached to said trunnion and movable therewith and a sight attached to said bar whereby movement of said gun cradle is transmitted to said sight.

BRYAN P. JOYCE.
